UNITED STATES PATENT OFFICE.

HENRY H. WILLIAMS, OF PHILADELPHIA, PENNSYLVANIA, ASSIGNOR TO THE TABOR MANUFACTURING COMPANY, OF PHILADELPHIA, PENNSYLVANIA, A CORPORATION.

LIQUID-FUEL-BURNING APPARATUS.

Application filed October 29, 1924. Serial No. 746,483.

The principal objects of the present invention are, first, to provide for safety, satisfactorily, economically and automatically heating a dwelling or the like with liquid fuel; second, to provide simple, reliable and comparatively inexpensive apparatus for use in the accomplishment of the first mentioned object; third, to automatically interrupt the supply of oil or liquid fuel in the event of the accidental extinguishment of the burner; fourth, to provide not only an initial adjustment for the burner but also a thermostatic adjustment for the burner; and fifth, to maintain a supply of water for a considerable length of time for the burner even though the city supply be interrupted.

Other objects of the invention will appear from the following description and the invention, generally stated, may be said to comprise an oil burning house heating system, including a vacuum feed oil burner, burner steam jet means heated by the burner, and thermostatic air connections for venting the vacuum of the burner to control the oil feed.

The invention also comprises the improvements to be presently described and finally claimed.

The invention relates to a burner of the jet type, the fuel being atomized by a supply of fluid under pressure which may be steam or compressed air or any other convenient medium. In the form of the invention illustrated, the atomizing medium is steam generated by the burner. The steam from the boiler is led to the burner and discharged through a nozzle into the burner tube creating in the burner passage or atomizing passage beyond the nozzle or orifice a jet of high velocity, the vacuum due to the velocity being utilized to raise the fuel to a reservoir from which it is fed to the burner by suction or gravity or both. The rate of combustion is in turn regulated by a second air passage leading to the burner jet by means of which the burner vacuum is controlled at the will of the operator or by means of a thermostat determining the rate of combustion. The burner vacuum contributes a very important element to the feeding of the fuel in addition to the function which it serves in raising the fuel to the tank, i. e., the burner suction or vacuum assists in the gravity feed and in atomization, and by controlling the vacuum, a wide

range of regulation of the operation is made available and extreme accuracy of regulation is attained.

My invention in its broader conception resides in the combination of a jet burner having a constricted passage, means for leading to said passage a supply of fluid under pressure whereby a jet is produced or actuated, a fuel lifting air passage leading to the jet whereby the vacuum due to the velocity of the jet is used to lift the fuel to a constant level reservoir, from which point it is fed to the burner, the feeding and atomization of the fuel being assisted by the burner suction, the tank being near or above the level of the jet, so gravity may be utilized, and a fourth passage in the nature of an air passage leading to the jet whereby the burner vacuum is controlled, in turn controlling the fuel feed and atomization, and hence the rate of combustion, the regulating passage being in turn controlled by a thermostat or manually operated means or both.

An important advantage incident to maintaining the supply of fuel below the level of the burner and raising it by the vacuum of a jet created by a steam pressure maintained by the heat of the burner itself to a point near or above the level of the burner, from which it is fed by gravity or by the burner vacuum or both, is that if by any chance the burner should be extinguished prematurely, the flow of fuel to the burner is stopped or limited to the small supply maintained in the constant level tank, greatly reducing the danger of fire, the waste of fuel and the various difficulties incident to flooding the furnace with oil.

The invention also relates to the details of the burner member having a longitudinal bore containing a plurality of plugs pierced by small central orifices forming the constricted portion and spaced apart or otherwise apertured at the ends providing the entrances to the lateral passages whereby the burner vacuum is utilized and controlled for the various purposes above recited.

The invention also relates to the combination of the burner with the boiler member and to the details of the boiler member, consisting of a steam drum or chamber within which is a fire tube which preferably extends through the steam chamber and into which the burner is directed, the burner, in

accordance with the preferred details of the device, being mounted on or directly connected to the steam drum.

In the following description reference will be made to the accompanying drawings forming part hereof and in which

Figure 1 is an end view, partly in section, of house heating oil burning apparatus embodying features of the invention.

10 Fig. 2 is a side view, partly in section, on the line 2—2 of Figure 1.

Fig. 3 is a view drawn to an enlarged scale and looking toward the left in Fig. 2 of the burner or atomizer, and

15 Fig. 4 is a sectional view taken on the line 4—4 of Fig. 3.

Referring to the drawings the burner proper or atomizer consists of a body 1 of tubular form and provided with three ports 20 leading from the central bore. Each port is connected with a tube or pipe 3, 5 and 6. Three tubular plugs or tips are mounted in the bore of the body 1, and they provide an orifice or nozzle 7, a space 8, a passage 9, 25 a space 10, and a passage 11, the passages 9 and 11 and the intervening portions of spaces 8 and 10 comprise the burner passage proper, subsequently referred to herein. When a jet of steam or other gaseous 30 fluid issues through the orifice 7, a partial vacuum is created in the spaces 8 and 10. The space 8 is connected by the pipe 5 with a vacuum system which lifts the fuel to a 35 point above the burner and which will be presently described. The space 10 is connected by the pipe 3 with a float valve 12 which in turn is connected by a pipe 13 to the vacuum system feed tank 14. The space 10 is also connected by the pipe 6 to the 40 thermostatic air valve 15 which, when open, permits air to enter the space 10 and decrease or altogether abolish the vacuum. According as the degree of vacuum in the chamber 10 is decreased a smaller quantity 45 of oil reaches the chamber 10, and thus this reduced quantity of oil is atomized by the jet passing out of the orifice or tube 9. When the valve 15 is closed the degree of vacuum or minus pressure in the chamber 10 increases, more oil reaches the chamber 10, and the quantity of oil atomized increases. The 50 steam generator consists of two tubes 16 and 17 welded or otherwise secured to end pieces and provided with a back leg 18. The back leg 18 is provided with a steam outlet connection into which the burner or atomizer 1 is screwed. There is also an inlet connection 19 for water under pressure. The flame from the burner 1 passes through the inner 55 tube 17 of the steam generator and the combustion in the inner tube may be regulated by the admission of air through the holes 20 in the end plate of the inner tube. Water from a source such as city mains, passes 60 through a valve 21, a check valve 22, an air

chambered tank 23, a valve 24, a strainer 25, and a pressure controller 26, and thence to the steam generator. This arrangement provides a supply of water at substantially constant pressure to the steam generator, and this supply is maintained for a considerable period of time in the event of failure of the main source of supply by reason of the air pressure at the top of the tank 23 and the check valve 22. Liquid fuel is lifted 75 from a storage tank, not shown because too well understood, in communication with the pipe 27 by the vacuum created in the chamber 8 of the burner and acting through the pipe 5 upon the vacuum tank 14. The pipe 27 communicates with the vacuum tank 14 by way of a strainer 28 and a pipe connection 29. From the vacuum tank 14 the fuel is piped by 13 to the float valve 12. The level of the liquid in the float valve 80 in respect to the level of the burner 1 can be raised or lowered by means of the adjusting nuts 30 and 31. The adjustment of the float valve governs the size of the flame, at any rate in part. The thermostatic strip 32 is carried by a spring strip 33 attached at one end to the frame 34, and acted upon at the other end by the manually positioned cam 35. The thermostatic strip 32 85 at its free end opens and closes the inlet to the pipe 6.

In use the float valve 12 is positioned by means of the nuts 30 and 31 to bring the fluid level to the height in respect to the burner 1 that is appropriate for combustion. The steam generator is preheated in order to supply a starting steam jet to the burner 1. The steam jet thereafter is supplied by the heat of the flame of the burner 1. Assuming the thermostatic valve 15 to be 100 closed, the vacuum effect in the chambers 8 and 10 facilitates feed from the float valve and also lifts oil or fluid fuel into the tank 14. If the thermostatic valve opens, the 105 vacuum effect at 10 is reduced or obliterated and the oil feed reduced. If the burner is accidentally extinguished, the generation of steam ceases and the oil feed stops except as there may be enough gravity feed to empty the tank 14 and float valve 12, but the 110 capacity of these is restricted so that the amount of oil reaching the shell 17 is negligible. The gravity feed from the float valve is constant as is also the water feed, and under those circumstances the burner is 115 automatically regulated by the vacuum effect and if accidentally extinguished both the oil and water feed are stopped.

Instead of preheating the steam generator in order to supply a starting jet to the burner 1, a jet of air furnished by a hand pump or otherwise may be used for that purpose.

In all cases of the application of the invention or of features of the invention the use of a steam jet is not essential because 120

the fluid supplying the jet may be other than steam, for example, air.

It will be obvious to those skilled in the art that modifications may be made in details of construction, arrangement and matters of mere form without departing from the spirit of the invention which is not limited to such matters or otherwise than as the prior art and the appended claims may 10 require.

I claim:

1. An oil burning apparatus comprising a burner tube, a nozzle directed into the tube, a steam boiler having a steam space, a fire 15 tube extending through the steam space, the burner being directed into the fire tube and the steam space being connected to the burner nozzle, setting up a jet from the nozzle through the tube, means for feeding 20 water against the fire tube, a fuel tank, a fuel pipe leading from the fuel tank to the burner tube, a fuel supply connected to the tank and means for utilizing the vacuum of the jet to move the fuel from the supply to 25 the tank, an air pipe connected to the burner tube leading air thereto to be mixed with the fuel by the action of the steam, and means for controlling the latter passage to 30 control the burner vacuum and the rate of combustion, said means comprising a thermostat and manually actuated means.

2. The method of burning liquid fuel which consists in releasing fluid under pressure through a constricted orifice creating 35 and maintaining a jet, utilizing the vacuum at the sides of the jet to raise the fuel and maintain a small supply of fuel at a constant level, leading the fuel from said supply to the jet and feeding it thereto utilizing 40 the vacuum of the jet in this connection, the vacuum and the velocity of the jet serving to atomize the fuel, supplying air to the sides of the jet and regulating the rate of combustion by changes of the burner vacuum 45 resulting from the control of the air supply.

3. The combination in a liquid fuel burner, of a passage having a constricted orifice, means for supplying fluid under pressure thereto creating a jet and setting up a vacuum at the sides of the jet, a constant level 50 fuel tank, means including an air pipe leading to said passage and a fuel pipe for utilizing the burner vacuum to maintain a supply of fuel in said tank, and a vacuum breaking pipe leading to the burner passage and means for varying the opening through 55 said passage for regulating the rate of combustion.

60 4. The combination in a liquid fuel burner, of a passage having a constricted orifice, means for supplying fluid under pressure to the orifice, creating a jet in the passage and setting up a vacuum at the sides 65 of the jet, a constant level fuel tank, means

including an air pipe leading to said passage and a fuel pipe and a fuel supply connected to said pipe for utilizing the burner vacuum to maintain a supply of fuel in said tank, a pipe connecting the constant level 70 tank to the burner orifice leading liquid fuel thereto, the vacuum acting as a feeding agency and assisting with the jet in the atomization of the fuel, means comprising a second air pipe connected to the burner passage in the vicinity of the orifice leading air thereto, means for controlling the opening in said pipe, thereby regulating the burner vacuum and the rate of combustion. 75

5. The combination in a liquid fuel burner 80 of a passage having a constricted orifice leading to the passage, means for supplying fluid under pressure to the orifice, creating a jet in the passage and setting up a vacuum in the passage at the sides of the jet, a constant level fuel tank, means including an air pipe leading to said passage and a fuel pipe connected to the supply for utilizing the burner vacuum to maintain a supply of fuel in said tank, a pipe connecting the lower 85 portion of the constant level tank to the burner passage leading liquid fuel thereto, the vacuum acting as a feeding agency and assisting and acting with the steam in the atomization of the fuel, means comprising a second air pipe connected to the burner in the vicinity of the orifice leading air thereto, thermostatic means for controlling the opening in said pipe, thereby regulating the burner vacuum and the rate of combustion. 90

6. In an oil burner, a nozzle, means for leading to and directing into said nozzle a supply of fluid under pressure, setting up a jet through the nozzle, a fuel tank and means connecting the lower portion of the tank to 105 the nozzle so as to utilize the jet vacuum in feeding the fuel, a vacuum pipe connected to the nozzle and to the upper portion of the fuel tank, utilizing the jet vacuum to supply fuel to the tank, and a vacuum breaking pipe leading to the nozzle and means regulating the opening through the last-mentioned pipe to regulate the vacuum at the sides of the jet and hence the rate of fuel feed to the nozzle and the rate of combustion. 110

7. In an oil burner, a nozzle, means for maintaining a supply of fluid under pressure and connections leading from said supply to the nozzle whereby a fluid jet is set up in 120 and through the nozzle, a tank for fuel at approximately the burner level, a feed pipe from the lower portion of the tank to the nozzle, a fuel supply with connections to said tank, and suction means operated by the burner vacuum for supplying fuel to the tank, means for regulating the fuel level in the tank to approximately the level of the nozzle, a vacuum breaking tube leading to the burner nozzle, and means controlling 125 130

the passage through said pipe to regulate the jet vacuum and hence the fuel supply to the burner and the rate of combustion.

8. In an oil burner, a nozzle, means for maintaining and leading to said nozzle a supply of fluid under pressure, maintaining a fluid jet issuing from the nozzle, an oil tank above the burner level, a constant level tank substantially at the level of the nozzle 10 and connected to the oil tank to receive oil therefrom, a feed connection from the constant level tank to the burner to supply fuel thereto, the jet vacuum being utilized in feeding the fuel to the nozzle, a passage leading to the nozzle to control the admission of air to the vacuum of the jet, and means controlling the opening through said passage regulating the jet vacuum and the fuel supply to the nozzle and hence the rate of combustion at the nozzle.

9. In a heating plant, an oil burner, a nozzle, means for leading to and directing into the nozzle a supply of fluid under pressure, thereby causing a fluid jet to issue from the nozzle, means for maintaining a fuel supply, and means controlled by the vacuum of the jet for feeding fuel to the nozzle, a vacuum regulating passage leading to the nozzle, and a thermostat located in the area 25 heated by the plant, and other means actuated by the thermostat varying the opening in said passage to regulate the fuel feed and the rate of combustion.

10. In a heating plant, an oil burner, a nozzle having a longitudinal passage, means for leading to and directing into said passage a supply of fluid under pressure, thereby setting up a fluid jet, the nozzle being provided with a chamber extending laterally 35 from the passage, the jet serving to create a vacuum in said chamber, a fuel tank and a fuel passage connecting the tank to said chamber, a vacuum regulating passage leading to said chamber, and a thermostat located in the area being heated by said plant, and means controlled by the thermostat for 40 controlling the opening through said regulating passage to regulate the vacuum in the chamber and hence the fuel feed and the rate of combustion.

11. In an oil burner, a nozzle having a longitudinal passage, means for leading to and directing into said passage a supply of fluid under pressure, setting up a fluid jet through 55 and issuing from the passage, the nozzle being provided with a chamber extending laterally from the passage, the jet serving to create a vacuum in said chamber, a fuel tank and a fuel passage connecting the lower portion 60 of the tank to said chamber, an air pipe leading to said chamber, and means for varying the opening through said pipe to

regulate the vacuum in the chamber and hence the fuel feed and the rate of combustion, a second vacuum pipe connected to 65 the nozzle passage and to the upper portion of the tank, a fuel supply and connections from said supply to said tank whereby the vacuum of the jet is utilized to move the fuel to the tank.

12. In an oil burner, a nozzle having a longitudinal passage, means for supplying fluid under pressure at one end of said passage, a jet-forming tapered portion in the passage adjacent said end, a chamber extending laterally from the passage just beyond said tapered portion, a vacuum pipe connected to said chamber, a second chamber also extending laterally from said passage beyond the first-mentioned chamber, an oil feed pipe leading to said second chamber, and a vacuum breaking passage also leading to said second chamber, means for controlling the opening through said vacuum breaking 80 passage to regulate the vacuum of the jet and the fuel consumption, a fuel tank connected to said fuel passage, and means operated by said vacuum pipe for supplying fuel to said tank.

13. In an oil burner, a nozzle having a longitudinal passage, means for supplying fluid under pressure at one end of said passage, the passage having a jet-forming tapered portion adjacent said end, a chamber extending laterally from the passage just 90 beyond said tapered portion, a vacuum pipe connected to said chamber, a second chamber also extending laterally from said passage beyond the first-mentioned chamber, an oil suction pipe leading to said second chamber, and a vacuum breaking passage also leading to said second chamber, and means for controlling the opening through said vacuum-breaking passage to regulate the vacuum of the jet and the fuel consumption, a fuel tank connected to said fuel passage, and means operated by said vacuum pipe for 95 supplying fuel to said tank, the tank having means for maintaining the fuel level in the tank at substantially a constant level.

14. The method of burning liquid fuel which consists in utilizing the heat generated to supply steam under pressure, passing said steam under pressure through a constricted orifice, creating and maintaining a jet, introducing small quantities of air into the nozzle just beyond the constricted area, utilizing the vacuum of the jet to feed the liquid fuel to the burner, and controlling the vacuum from a point of application of the resulting heat by varying the said air supply to the jet to regulate the rate of fuel feed and the rate of combustion.

HENRY H. WILLIAMS.
